[57] CLAIM

The ornamental design for a rail for an automatic monorail system, as shown.

DESCRIPTION

FIG. 1 is a front, right-side and top perspective view of a rail for an automatic monorail system showing our new design;

FIG. 2 is a front elevational view of the rail for an automatic monorail system shown in FIG. 1;

FIG. 3 is a right-side elevational view of the rail for an automatic monorail system shown in FIG. 1;

FIG. 4 is a rear elevational view of the rail for an automatic monorail system shown in FIG. 1;

FIG. 5 is a left-side elevational view of the rail for an automatic monorail system shown in FIG. 1;

FIG. 6 is a top plan view of the rail for an automatic monorail system shown in FIG. 1; and,

FIG. 7 is a bottom view of the rail for an automatic monorail system shown in FIG. 1.

FIG. 1
